(57) **CLAIM**

The ornamental design for an alarm clock pill dispenser, as shown and described.

DESCRIPTION

FIG. 1 is a perspective view of an alarm clock pill dispenser showing our new design;

FIG. 2 is a front view thereof;

FIG. 3 is a side view thereof;

FIG. 4 is a side view thereof;

FIG. 5 is a back view thereof;

FIG. 6 is a top plan view thereof; and,

FIG. 7 is a bottom plan view thereof.

Broken lines are used to indicate structure that does not form part of the claimed design.
